APPARATUS FOR CASTING UNDER PRESSURE

Filed Nov. 21, 1927

Inv. by
Erik Jorgen-Jensen
By Lundbeck & Søn A/S
Copenhagen, Denmark

UNITED STATES PATENT OFFICE.

ERIK JORGEN-JENSEN, OF EDGBASTON, BIRMINGHAM, ENGLAND.

APPARATUS FOR CASTING UNDER PRESSURE.

Application filed November 21, 1927, Serial No. 234,772, and in Denmark March 22, 1927.

My invention relates to the production of castings under pressure.

Within recent years the use of air pressure in foundry practice has found favour for the reason that good filling of the moulds and greater density of metal can thereby be secured. The apparatus employed for pressure casting however, frequently suffers from the drawback that the crucible containing the molten metal, after a period of use, becomes cracked or ruptured for the reason that it is unable to withstand the differential pressure to which it is subjected.

To avoid this drawback it has been proposed to enclose the crucible in a cover or bell to which the air pressure is supplied so that the crucible, both externally and internally, is subjected to uniform pressure conditions. With such an arrangement there still exists the drawback that it is not readily possible to evacuate the crucible of all molten metal in the casting operation and consequently the outlet therefrom and the inlet to the mould are likely to become choked with chilled metal.

The apparatus according to the present invention is characterized by the fact that the molten metal, by combined air pressure and syphonic action, is caused to run through a tube in the bottom of the crucible, while the said crucible is surrounded by a compressed air bell in such a manner that the walls of the crucible are not exposed to any differential pressure.

One construction of the improved apparatus is illustrated in vertical longitudinal section in the accompanying drawing.

Referring to the latter, 1 is a plate below which the mould 2 is disposed, in such a manner that the gate 3 of the same is situated directly below the corresponding opening 4 in the plate 1. Above this opening there is placed on the plate a crucible 5 at the centre of which there is provided a tube 6 the mouth of which, as shown, is situated above the normal level of molten metal in the crucible, and which is adapted, when the crucible is placed in position, to communicate with the opening 4 of the plate 1 and the gate 3 of the mould 2.

Over the crucible and on the plate there is placed a bell 7 from which a smaller bell 8 is suspended, which latter, when the bell 7 is in position, projects down to the bottom of the crucible and encircles the tube 6, holes being

provided, however, at the bottom edge of the bell 8, in such a manner that the masses of molten metal inside and outside of the bell 8 will be in communication with one another. By way of a pipe 9 compressed air may be directed into the bell 7, in such a manner that the molten metal contained in the crucible 5 outside the bell 8, owing to the air pressure, will be pressed through the holes at the lower edge of the bell 8 up the interior of the latter and down the tube 6 into the mould 2. As the quantity of molten metal in the crucible 5 may be adjusted to correspond to the volume of the mould, the air pressure, after the mould has been filled, will act directly on the metal contained in the mould. Furthermore, owing to the provision of the bell 8 and the particular arrangement of the latter with respect to the tube 6, it will be observed that when the molten metal flows into the tube due to the pressure applied to it a syphonic action will be set up. This action will not only assist in the evacuation of the crucible but will augment the air pressure acting directly on the metal in the mould.

In the herein described embodiment the constructional details have been omitted for the sake of simplicity, but obviously means must be provided for securing a connection between the mould 2 and the plate 1 and between the latter and the bell 7 as well as for suspending, in suitable manner, the interior bell 8 from the outer bell 7. In the latter respect the means may comprise a spring 10 as shown.

What I claim and desire to secure by Letters Patent of the United States is:

1. Apparatus for casting under pressure, comprising a crucible adapted to contain molten metal, an outlet from said crucible, means for causing the molten metal to flow through said outlet by combined air pressure and syphonic action, and a compressed air bell surrounding said crucible suchwise that the walls of the crucible are not exposed to differential pressure.

2. Apparatus for casting under pressure, comprising a crucible adapted to contain molten metal, an outlet from said crucible, a mould, means for causing the molten metal to flow through said outlet into said mould by combined air pressure and syphonic action, and a compressed air bell arranged suchwise that the walls of the crucible are free from exposure to differential pressure, said air

pressure acting directly on the metal in the mould and being augmented by said syphonic action.

3. Apparatus for casting under pressure, comprising a crucible adapted to contain molten metal, a tube extending from the bottom of said crucible and having an outlet adapted, when the crucible is placed in position to communicate with an inlet to a mould, 10 a bell covering said crucible, means for supplying air under pressure to the interior of the said bell, and another bell arranged within said first mentioned bell and covering said tube, for the purpose set forth.
- 15 4. Apparatus for casting under pressure, comprising a crucible adapted to contain molten metal, a tube extending upwardly from the bottom of said crucible, an outlet to said tube adapted to communicate with an inlet to a mould, a bell adapted to cover said crucible, means for supplying air under pres-

sure to the interior of said bell, another bell arranged within said first mentioned bell and covering said tube, and means for suspending said second mentioned bell from said first mentioned bell, for the purpose set forth. 25

5. Apparatus for casting under pressure, comprising a mould, a crucible adapted to contain molten metal, a tube extending from the bottom of said crucible and having 30 an outlet adapted to communicate with an inlet to said mould, a bell covering said crucible, means for supplying air under pressure to the interior of said bell, and another bell situated within said first mentioned bell 35 and around said tube the arrangement being such that the crucible is evacuated of molten metal by combined air pressure and syphonic action and such that said air pressure acts directly on the metal in the mould and is augmented by said syphonic action. 40
